(57) **CLAIM**

The ornamental design for a two connector mounting structure, as shown and described.

DESCRIPTION

FIG. 1 is a perspective top view of a “two connector mounting structure” showing my new design;

FIG. 2 is a perspective bottom view thereof;

FIG. 3 is a top plan view thereof;

FIG. 4 is a bottom plan view thereof;

FIG. 5 is a side view thereof; the opposite side being a mirror image thereto;

FIG. 6 is a front view thereof; and,

FIG. 7 is a rear view thereof.
